DESIGN FOR A DRESS

Samuel Berkowitz, New York, N. Y.

Application January 26, 1942, Serial No. 105,409

Term of patent 3½ years

To all whom it may concern:

Be it known that I, Samuel Berkowitz, a citizen of the United States, residing in New York city, in the county of New York and State of New York, have invented a new, original, and ornamental Design for a Dress of which the following is a specification, reference being had to the accompanying drawing, forming part thereof.

Fig. 1 is a front view of a dress showing my design,

Fig. 2 is a rear view of the dress shown in Fig. 1.

I claim:

The ornamental design for a dress, substantially as shown.

SAMUEL BERKOWITZ.
